UNITED STATES PATENT OFFICE.

EDWARD B. LEGGETT AND THOMAS W. APPLEYARD, OF NEW YORK, N. Y., ASSIGNEES
TO LOREN M. COWDREY AND FREDERICK WINKHAUS, BOTH OF NEW YORK, N. Y.

FIREARM.

1,007,709.

Specification of Letters Patent.

Patented Nov. 7, 1911.

Application filed October 19, 1910. Serial No. 587,807.

To all whom it may concern:

Be it known that we, EDWARD B. LEGGETT and THOMAS W. APPLEYARD, citizens of the United States, and residents of the borough 5 of Brooklyn of the city and State of New York, have invented new and useful Improvements in Firearms, of which the following is a specification, reference being made to the accompanying drawings, forming 10 a part thereof.

The invention relates to fire arms in general and particularly to that type known as revolvers.

This invention is directed to the following 15 enumerated features and also to other features not specifically enumerated at this point but all of which are clearly described and set forth in the specification and claims forming a part thereof. Some of the features thus referred to are, *a*, the means for locking the rear end of the barrel to the frame; *b*, the hammer and operating mechanism therefor; *c*, the means for locking the rear end of the cylinder, at the central 20 portion, to the frame of the fire arm at a time when the firing is to take place, said means also being connected to the firing pin and operable by the hammer; *d*, the means for holding the cylinder from rotating and also 25 for holding the cylinder so that a cartridge hole in the cylinder is in proper position relative to the bore of the barrel at the time of firing and, *e*, the means for retaining the cylinder in place upon the barrel at the time 30 35 the cartridge shells are being extracted from the cylinder by the extractor.

In the drawings above referred to, Figure 1 is a side view of the revolver partly in section showing the positions the parts normally occupy when the revolver is not being used. Fig. 2 is a view similar to Fig. 1 showing the position the parts occupy prior to the release of the hammer before firing. Fig. 3 is a side view partly in section of a 45 part of the revolver showing the means for retaining the cylinder in place on the barrel and also the means for locking the rear end of the barrel to the frame. Fig. 4 is a side view partly in section of a part of the revolver showing the position which the member for retaining the cylinder upon the barrel occupies when the cylinder is being removed from the barrel. Fig. 5 is a sectional view taken on line 5—5 of Fig. 2.

Fig. 6 is a sectional view showing the position of the cylinder, frame, and combined firing pin and locking bolt at the time of firing. Fig. 7 represents detail views of the combined firing pin and locking means, and Fig. 8 shows front and side views of the hand, the lifter, the spring therebetween and a part of the trigger.

The frame of the revolver is designated by 1 and upon this is pivotally mounted the barrel 2 carrying a cylinder 23. This cylinder is provided with any well known type of shell extracting means and as the same is not the subject of my invention it will not be further described.

In order to lock the rear end 5 of the barrel 2 to the frame 1, the latter is provided with a projection 3 which is slotted and also with a recess portion 3^a. The rear end 5 of the barrel is shaped so as to fit the frame and is recessed so as to receive the projection 3 carried by the frame. This rear portion of the barrel is also provided with a sliding spring pressed bolt 4 which is flattened at 4^b so as to enter the slot of the projection when forced forward against the spring by pressure applied to the part 4^a, and when the rear portion of the barrel is being swung to normal position. This bolt is also so formed that when the barrel and frame are in normal position relative to each other a part 4^a of the bolt will enter the recess 3^a and part 4^c of the bolt will engage overhanging portions on the projection 3 and thereby form a double locking means between the barrel and frame. 90

A folding trigger 7 is pivoted at 7^a to the frame and on the rear end thereof there is pivotally mounted the front sear or lifter 8 and the hand 20. The front sear or lifter 8 and the hand 20 are pressed apart by the spring 21 and are so arranged that when the trigger is pulled the sear or lifter will force back the hammer and simultaneously therewith cause a revolving of the cylinder 23. But the revolving of the cylinder will not take place until after the cylinder stop 25 has been withdrawn from the notch 24, in the cylinder 23, in a manner which will be hereinafter described.

The hammer 6 is continually forced forward by a spring pressed rod 11 and is pivotally connected at the point 10^a to an actuating lever 10, which is pivoted on the

frame at point 9. Both the actuating lever and the hammer are provided with openings larger than the pivot or fulcrum member at 9 into which said member enters. The free forward end of the actuating lever 10 has a slidable engagement with the rear end of the trigger 7 and a pull upon the latter will impart an upward movement to the forward end of the actuating lever and a downward movement of the rear portion to which the hammer 6 is pivotally connected since the actuating lever swings about the pivot or fulcrum member at 9. The pull on the trigger will also cause the front sear or lifter 8 to press upon the hammer and force it against the pressure of the spring pressed rod and this will cause the hammer to swing around the pivotal point 10^a, which has been lowered, until the pivot or fulcrum member at 9 is in the lower portion of the openings referred to. Now when the front sear or lifter disengages from the hammer the latter will be forced forward and downward due to the spring pressed rod and the forward end of the hammer will engage the combined firing pin and locking bolt at the point 12^a and will force them to firing and cylinder locking position. This engagement of the combined firing pin and locking bolt by the forward end of the hammer will take place due to the fact that the point 10^a around which the hammer swings has been lowered and due to the fact that this swinging can take place since the opening in the hammer 6 in which the pivot or fulcrum member at 9 is located will permit the swinging movement of the hammer. The opening in the actuating lever is made larger than the pivotal or fulcrum member at 9 to permit a change in distance between the pivot or fulcrum member at 9 and the pivotal connection between the hammer and lever at the point 10^a so that the hammer can swing freely forward without any cramping taking place between the two said points due to the walls which define the opening in the hammer being at variable distances from the pivotal connecting point 10^a. It will be observed that the slot in the hammer is not concentric with the pivotal point 10^a and therefore when the hammer swings about said point 10^a there is, due to the engagement of the wall or cam portion of the slot in the hammer with the pivotal member 9, a movement of the point 10^a from said pivotal or fulcrum member 9 carried by the frame and this movement is permitted to take place due to the elongated slot in the front sear or lifter 8 which slot permits the sear or lifter to move as a whole. The spring pressed rod 11 for forcing the hammer forward, after the latter has been released by the front sear or lifter, is provided with an adjustable nut 17 which engages one end of the coiled main spring

13 and this serves as a means for regulating the compressing force of the spring 13 upon the rod. Carried by slots in the front and rear handle portions 18 and 19 respectively of the frame and in a manner to permit removal therefrom by a lateral movement is main spring guide bar 14 through which the rod 11 above referred to passes and which also supports one end of the main spring 13. This bar is provided with a hole 15 through which screws for the handle may pass in order to hold the handle in place.

The combined firing pin and locking bolt 12 comprises the locking bolt 12^b and the firing pin 12^c both of which are integrally connected and both of which are slidably mounted in the frame 1. The locking bolt 12^b is so positioned that it is in axial alignment with the cylinder and is constructed so that when the firing pin is in the position which it must occupy in order to cause the cartridge to explode, the locking bolt will be in an opening 23^a in the cylinder so that the cylinder and frame will be held in proper position relative to each other. The upper rear portion of the combined firing pin and locking bolt is recessed so that the end of the hammer will normally rest therein when not in use.

In order to hold the cylinder from rotating and also in order to hold the cylinder so that one of the cartridge openings therein is in alignment with the bore of the barrel, there is provided a cylinder stop 25 which is located in stop slot hole 26 and which is pivotally mounted upon the frame. This stop is normally held in place by a spring and has an end which enters notches 24 in cylinder 23. A spring pressed latch 22 is slidably mounted in the trigger and is located so that a pull upon the trigger will first cause a sufficient movement to be imparted, by means of the latch, to the cylinder stop member to swing the end of the stop member, which is in one of the notches 24 away from the cylinder 23 so as to permit the latter to revolve when caused to do so by the hand 20 previously described. Before, however, the trigger has reached the limit of its rearward movement, this latch 22 will become disengaged from the cylinder stop member and the spring will cause the stop member to return to its normal position when the stop and notched portions are in juxtaposition.

The cylinder retaining means can be clearly seen in Figs. 2, 3 and 4. This means comprises a member 29 which is held in normal position by means of the spring 30 and when in said position abuts against a portion of the frame 30^a which prevents the end 29^a thereof from being forced rearwardly. This end 29^a overlaps the cylinder 23 but is located to the rear of the end of the cylinder 23 sufficiently to permit said

end to be swung forward up out of the way of the cylinder so that the latter can be withdrawn from the barrel when a rearward movement is imparted thereto.

In Fig. 8 can be seen the specific construction of the cylinder turning hand 20, the sear or lifter 8 and the spiral compression spring 21 therebetween. Integral with the hand 20 is a pin 20^a which enters openings 7^a in the spaced lugs or ears 7^b of the trigger 7. Between these ears there is pivoted on the pin 20^a the sear or lifter 8 which has a portion 8^a overlapping the hand 20. The hand and also the sear or lifter are both recessed to receive the ends of the spiral compression spring 21. It will be apparent that this construction avoids the use of a spring which is hard and difficult to make and utilizes in place thereof a spiral spring which is one of the simplest springs that can be made and it will also be apparent in this construction the spring forces are allied in a very advantageous and simple manner to the hand and also to the sear.

It is obvious that various changes and modifications may be made without departing from the spirit and scope of our invention.

We claim as our invention:

1. In a device of the character described, the combination of a frame, a stationary fulcrum member carried thereby, a hammer actuating lever engaging the fulcrum member and movable relative thereto, and a hammer pivotally connected to the lever at one side of the fulcrum point, the hammer being provided with an opening therein larger than the fulcrum member into and through which the fulcrum member extends.

2. In a device of the character described, the combination of a frame, a fulcrum member carried thereby, a trigger movably mounted on the frame, a hammer actuating lever operable by a movement of the trigger and a hammer pivotally connected to the actuating lever at one side of the fulcrum member, the hammer actuating lever and the hammer both being provided with openings therein larger than the fulcrum member and in which the fulcrum member enters.

3. In a device of the character described, the combination of a frame, a fulcrum member carried thereby, a trigger movably mounted on the frame, a hammer actuating lever positioned so as to be operated by a movement of the trigger, a hammer pivotally connected to the lever at one side of the fulcrum point, a firing pin, and a hammer lifter or sear operated by a movement of the trigger, the actuating lever and the hammer being provided with elongated slots in which the fulcrum member is located, the parts being so connected and arranged that in one position when the hammer is down it will not engage the firing pin member but when

tripped from full cock it will engage the firing pin member and force the firing pin into firing position.

4. In a device of the class described, the combination of a frame carrying a firing pin, a hammer pivoted upon a member which is movable relative to the firing pin, and a member between the hammer and frame carried by the latter which enters an elongated slotted portion whereby as the hammer moves the movable member will be caused to move to control the position of the hammer.

5. The combination of a frame, a hammer having a shiftable pivotal connection to the frame, and means between the hammer and frame to cause the pivotal connection to shift by the movement of the hammer from cocked to firing position.

6. The combination of a frame, a pivoted hammer, camming means between the hammer and frame and a trigger, the pivotal point of the hammer being moved during a forward movement of the hammer by said camming means.

7. In a device of the class described, the combination of a frame, a hammer having a pivotal connection to the frame that can be changed, a movable trigger and means extending between the frame and hammer for causing the pivotal portion of the hammer to be changed when the hammer moves forward, the hammer being so mounted and connected to the frame and so operated by the trigger that the pivotal portion of the hammer will be changed relative to the frame by a pull of the trigger to move the hammer backward.

8. In a device of the class described, the combination of a frame, a hammer, a spring pressed rod engaging the hammer, handle side pieces, and a member supported by the frame so as to permit a removal therefrom of said member, said member having an opening to receive the rod and an opening to receive a screw which is utilized to hold the handles in position on the frame.

9. The combination of a frame, a barrel, a cylinder carried thereby, a member comprising a firing pin and a locking bolt carried by the frame, and a hammer for causing movement of said member whereby the firing of a cartridge may be effected and the locking bolt will lock the cylinder to the frame by a movement of the member longitudinally relative to the barrel.

10. The combination of a frame, a cylinder, a movable locking bolt carried by the frame adapted to engage the rear end of the cylinder and a hammer which is so positioned that the bolt is moved to cylinder engaging position by a movement of the hammer.

11. The combination of a frame, a cylinder, a movable locking bolt carried by the

frame adapted to engage the rear end of the cylinder and a hammer which is so positioned that the bolt is moved to cylinder engaging position by a forward movement 5 of the hammer.

12. The combination of a frame, a cylinder, a movable locking bolt carried by the frame adapted to engage the rear end of the cylinder by a movement of the bolt 10 longitudinally relative to the cylinder and a hammer which is so positioned that the bolt is moved to cylinder engaging position by a movement of the hammer.

13. The combination of a barrel and cylinder mounted thereupon, a frame having a movable locking bolt which is in alinement with the axis of the cylinder when the cylinder is in firing position relative to the frame 15

and a hammer, the locking bolt being moved by the movement of the hammer. 20

14. The combination of a frame, a barrel carried thereby, a cylinder located between the frame and barrel and a combined firing pin and locking bolt carried by the frame adapted to lock the rear end of the cylinder 25 to the frame when the pin moves to cartridge firing position.

This specification signed and witnessed the 18th day of October, A. D., 1910, in the city of New York, in the State of New 30 York.
